UNITED STATES PATENT OFFICE.

CARL AUGUST PFENNING, OF BARMEN, GERMANY.

FASTENER FOR GLOVES, GAITERS, &c.

SPECIFICATION forming part of Letters Patent No. 295,583, dated March 25, 1884.

Application filed August 6, 1883. (No model.)

To all whom it may concern:

Be it known that I, CARL AUGUST PFENNING, of Barmen, Germany, have invented a new and useful Fastener for Gloves, Gaiters, 5 Boots, and Bags, of which the following is a specification.

My invention has for its object the easy and rapid fastening of gloves, gaiters, boots, or bags by means of buttons.

10 In describing the invention reference will be made to the accompanying drawings, in which Figure 1 is a perspective view, Fig. 2 a cross-section, and Fig. 3 a plan, while the remaining figures, 4, 5, 6, 7, 8, 9, 10, and 11, illustrate details and modifications.

15 The button consists of a solid body, *a*, rounded hemispherically at the top, with a radial bore, *o*, inside of which a pin, *i*, is fitted, so that the pressure of the spring *f*, coiled 20 round it, always tends to keep the knob *b* of the said pin protruding over the button. To prevent the knob *b* from falling out of the bore *o*, the edges of the latter are slightly bent inward after the pin has been introduced into the 25 bore, so as to afford a rest for the thick hind part of the knob. The length of the pin is made so as to allow the knob to be pressed into the bore. This knob has for its purpose to prevent the eyelet *e*, after it has been pressed 30 over the button, Figs. 2 and 3, from sliding back over the protruding part of the button. For fastening the button to the leather, the solid body *a* is provided at the bottom with a protuberance, *g*, hollowed out conically or cylindrically. (See section, Fig. 10.) The button 35 stands on a perforated plate, *s*, laid on the leather, and a second similar plate, *s'*, is laid at the bottom, so that the protuberance *g* passes through the hole of the plate. The 40 edges of the protuberance are then bent outward and the leather is pressed between these two plates, whereby the button is firmly secured.

Instead of the eyelets *e*, a lock-plate, *p*, may be used, as shown in Fig. 4, which plate has 45 an aperture slightly larger than the diameter of the button. The button may also be fastened to the leather, in the usual way, by riveting it on a plate, *l*, provided with points which are bent over the under side, as shown 50 in Figs. 6 and 7.

Fig. 8 shows another modification. The button is bored diametrically and provided with two knobs, *s*, placed opposite each other. The pin of the one enters the hollow pin of the other, and the coil between them presses 55 the two knobs outward in the same way as already described, using the same means for preventing their falling out of the bore of the button.

What I claim is—

1. A button for gloves, gaiters, boots, or bags, consisting of a solid body, *a*, having a radial bore, *o*, into which is fitted a movable pin and a coiled spring, the pin being provided 65 with a knob pressed outward by the said spring, substantially as described, and for the purpose set forth.

2. The combination of a solid button, *a*, fixed to one of the two parts to be united, and 70 having a radial bore, with a movable pin, *i*, fitted into the said bore, and a coiled spring, *f*, secured in the said bore, so as to press the pin outward, and an eyelet fixed to the other of the two parts to be united, substantially as 75 described.

In testimony whereof I have signed this specification in the presence of two subscribing witnesses.

CARL AUGUST PFENNING.
